FIG.7

FIG.8

FIG.9

FIG.10

FIG.11

FIG.12

FIG.13

FIG.14

FIG. 1 is a front elevation of a holder for a writing instrument, showing my new design.

FIG. 2 is a side elevation thereof rotated 90° to the left of FIG. 1.

FIGURES 3 to 14 inclusive are sections on the lines 3—3 to 14—14, respectively, of FIGURE 1.

I claim:

The ornamental design for a holder for a writing instrument, as shown.
